UNITED STATES PATENT OFFICE

NELS H. NELSON, OF DAYTON, OHIO, ASSIGNOR TO MERCHANTS ASSOCIATION, INC., OF DAYTON, OHIO, A CORPORATION OF OHIO

PRINTING PRESS

Original application filed July 26, 1930, Serial No. 470,824. Divided and this application filed July 13, 1931. Serial No. 550,403.

This invention relates to improvements in feeding mechanism for paper sheets, for feeding the sheets to a printing press.

It is the object of this invention to provide an improved feeding table for use in connection with a paper feeding mechanism for feeding sheets of paper to a printing press.

It is particularly the object of this invention to provide a receiving table on which there are means for aligning the sheets of paper and maintaining the sheets in a position to be fed to a printing press.

These and other objects and advantages will appear from the following description taken in connection with the drawings:

This application is a division of application Ser. No. 470,824, filed July 26, 1930.

Referring to the drawings:

Figure 1 is a top plan view of the receiving table shown in connection with a printing press.

Figure 2 is a front elevation of the printing press with the associated feeding means.

Figure 3 is a fragmentary view of the rear guide for a stack of sheets of paper.

Figure 4 is a view at right angles to Figure 3.

Figure 5 is a perspective view of the feeder bar clamp.

The feeding table is shown in connection with a suction-operated feeding means for delivering sheets of paper, one at a time, from a stack to a printing means. In order to support the stack of sheets of paper there is provided a platform 1, from which there extends upwardly a plurality of feed table guides 2. These guides engage the feed table 3 and guide it in its vertical movement.

For moving the table up and down in a vertical direction there extends downwardly from the table through the platform a plurality of feeder racks 4, which are engaged by suitable operating gear located beneath the platform. The operation of the racks 4 for the elevation of the feed table is no part of this invention. Therefore the racks are not further described.

Supported on each side of the platform and extending upwardly in the form of a loop or bow there is a feeder bar 5. This

bar extends upwardly from each side of the platform and across the top of the platform, and over the feed table, as clearly shown in Figure 2. The horizontal part of the guide bar 5 has attached thereto a plurality of clamps 6, which carry transversely of the bar rear guide bars 7. In the present instance there are two of these rear guide bars, each of which has on one end rear guide fingers 7a. This rear guide is in the form of a V with the open end downward, and engages the edge of a stack of paper located on top of the feed table. These rear guides may be arranged longitudinally of the guide bar and they may be arranged or adjusted transversely of the bar, thereby accommodating sheets of different lengths and different widths.

The sheets are fed by means of suction tubes, and in order that the sheets may be easily fed there is provided adjacent the stack of sheets a plurality of flutter nozzles 8, connected to tubes 9 which lead to some suitable source of air pressure. Suitably supported on each side of the platform is a feeder arm 10, which has on its upper or outer end a feeder bar or frame 11. This frame or bar 11 has a plurality of shoes 12, each of which is supported by a shoe holder 13. Each feeder shoe has connected thereto an air tube 14 through which air is delivered to the shoes, or through which air is drawn for taking up a sheet of paper on top of the pile for delivery to the printing press. The ends of the feeder arms remote from the frame 11 are pivotally attached to a feeder arm shaft 15, suitably supported adjacent the platform. The arms 10 swing with the shaft 15.

When it is desired that a strip of paper be removed from the stack the feeder shoes are brought to the top of the stack, suction is produced in the shoes, whereby a sheet of paper is picked up and by a swinging movement of the feeder arms the sheet of paper is transferred to a transfer table 16, where it is released for transmission to the press for printing purposes. The printing mechanism is no part of the present application. After the sheet of paper has been print-

ed it is again removed to a delivery table 17. Suitably supported by some part of the printing mechanism there are brackets 19 which support a transverse supporting rod 18.

6 Extending from the brackets 19 in the present instance two in number, are fingers 20, one from each bracket. On each finger is a longitudinal guide 21, adjustably supported on the finger 20. There is also on each finger 20 a rear aligning guide 22, which extends partly across and above the table for properly aligning sheets of paper transferred to the receiving table. There is also extending from the rod 18 an arm 23.

16 This arm has thereon a separator 24 used for separating the sheets into two different stacks as they are fed to the receiving table. This separator is used when two sheets at a time are being fed from the feeding table for printing purposes. The apparatus is adapted to feed one or two sheets of paper, depending upon the adjustment. This separator will separate sheets into two different piles, the arm extending across the table 25 slightly above the table with the separator extending from the arm toward the top of the table. The stack of sheets of paper located on the feeding table for delivery to the feeding press is indicated by the numeral 25. There may be one or more of these stacks 30 of sheets of paper, depending upon whether one or two sheets are being printed at a time.

I desire to comprehend within my invention such modifications as may be embraced 35 within my claims and the scope of my invention.

Having thus fully described my invention, what I claim as new and desire to secure by Letters Patent, is:

20 1. In combination, a feeder table adapted to support a plurality of stacks of sheets, an arch member carried by said table arranged over and transversely of said sheets, supporting clamp members mounted over the stacks 25 of said sheets adjustably on said arch, transversely adjustable members carried thereby, and adjustable depending fingers supported by each transversely adjustable member engaging the backs of the stacks of said sheets.

50 2. In a printing press, a feeder table, an arch member extending transversely over the table, a plurality of guide bars supported by the arch member for adjustment longitudinally and transversely of the table, and guide 55 fingers on each guide bar.

3. In a printing press, a feeder table, a feeder bar extending over the table, a plurality of clamp members adjustable longitudinally of said feeder bar, and a guide for 60 each clamp member adjustable transversely of said feeder bar.

4. In a printing press, a feeder table, a feeder bar extending over the table, a plurality of clamp members adjustable longitudinally of said feeder bar, a guide bar

supported by each clamp member for adjustment transversely of the feeder bar, and guide fingers on each guide bar.

In testimony whereof, I affix my signature.

NELS H. NELSON.
